**PILOT LIGHT FOR AN EXPLOSION PROOF
ENCLOSURE OR SIMILAR ARTICLE**

Don J. Arneberg, Milwaukee, Wis., assignor to Square D
Company, Park Ridge, Ill., a corporation of Michigan

Filed July 20, 1960, Ser. No. 61,448

Term of patent 14 years

(Cl. D26—8)

FIG. 1

FIG. 2

FIG. 3

FIG. 1 is a perspective view of a pilot light for an explosion proof enclosure or similar article, showing my new design;

FIG. 2 is a front elevational view; and

FIG. 3 is a side elevational view, the opposite side being substantially a mirror image thereof.

I claim:

The ornamental design for a pilot light for an explosion proof enclosure or similar article, substantially as shown and described.
